UNITED STATES PATENT OFFICE

2,648,029

SELF-BALLASTING GASEOUS DISCHARGE
LAMP

Walter J. Dremann, North Warren, and Robert E. Dunham, Warren, Pa., assignors to Sun Ray Electric, Inc., Warren, Pa., a corporation of Delaware

Application December 16, 1949, Serial No. 133,455

2 Claims. (Cl. 315—52)

1

The present invention relates to electrically operating a gaseous discharge device generally and more specifically to such devices which are self-ballasting, that is, which require no external reactor or current limiting device.

An object of this invention is to lower the overall cost of fluorescent lamp illumination by providing a lamp which operates without the auxiliary external reactor which is now in general use to limit the current flow through the lamp. Such external reactors or ballasts are heavy, bulky and costly.

Another object of the invention is to provide a source of visible or ultra-violet rays of conventional appearance and so designed that it can be manufactured by using the present production methods.

Other objects and features of the invention will become apparent when the following description is considered in connection with the annexed drawing which is a broken cross-sectional view of a lamp illustrating our invention, the view also including schematic wiring connections.

The lamp of our invention comprises the usual glass envelope 10 having therein a gaseous conductive atmosphere. The envelope 10 contains two filamentary cathodes 11 and 12 which cathodes are coated in the usual manner with thermionic emitting materials. In the usual manner one leaf from cathode 11 extends through a press 13 and is connected to an external terminal 14. In like manner a lead from one end of cathode 12 extends through press 15 and is connected to a terminal 16.

In accordance with our invention the opposite end of cathode 11 is connected to a resistor 17 which is in turn connected by means of a lead passing through the press 13 to a terminal 18. The construction at the opposite end of the lamp is substantially similar, that is, the lower end of cathode 12 is connected to a resistor 20 which is in turn connected by a lead passing through the press 15 to a terminal pin 21.

It will be noted that the terminals 15 and 16 are smaller than the terminals 18 and 21. This is true because it is necessary that the lamp be polarized in order to assure that the limiting resistors 17 and 20 are automatically placed in series as respects the operating current when the lamp is in operation and subsequent to its original ignition.

As is indicated in the diagram, the terminals 14 and 16 are connected by the leads 22 and 23 respectively to a conventional starter 24, and the terminals 18 and 21 are connected to the usual 110 volt lighting circuit.

2

It is preferable that the direct leads to the cathodes 11 and 12 from terminals 14 and 16, respectively, be insulated between the press and the cathode end in the manner shown at 19. This insulating of the leads assures that there will be no arc-over within the tube between the leads connected to terminals 14 and 18 or 16 and 21 as the case may be.

The gaseous atmosphere preferred in the envelope of this tube is argon or krypton or a mixture thereof supplemented in the usual manner with a minute quantity of mercury vapor which is usually introduced in the form of metallic mercury. The cathodes 11 and 12 are usually coiled-coil filaments of tungsten coated with an electron-emitting substance such for example as barium and strontium oxides to which may be added calcium oxide and calcium carbonate.

The current limiting resistors 17 and 20 are preferably made of alloys of iron and chromium in order to reduce expense although they may be made of high melting point material such as tungsten or molybdenum. The mechanical design of these resistors as well as their electrical properties are extremely important to the proper functioning of our invention.

The operation of this device is as follows. The lamp is put into use by closing of the usual manual switch in the 110 volt supply line. The circuit is initially completed therefore through the resistor 17, cathode 11, starter 24, cathode 12 and resistor 20. The starter operates after a short period of time to open the connection between terminals 14 and 16 and the arc then strikes across the lamp. During one-half cycle of the alternating current the current enters the lamp through the terminal 18, is limited in value by passing through the resistor 17, and flows as an electron flow from cathode 11 through the conductive atmosphere of the gas to the point of highest opposite polarity in the lamp, namely, the right hand end of resistor 20. On the following half-cycle current flows through terminal 21, resistor 20, and thence across the lamp through the conductive gas to the point of highest potential at the other end of the tube, namely, the left end of resistor 17.

In the design of resistors 17 and 20 it is important to achieve a balance between the overall length and the voltage across the resistor, in order that the voltage per inch across the resistor be less than the voltage per inch required to cause ionization of the gaseous atmosphere. If the voltage per inch were allowed to exceed the per inch voltage breakdown potential of the gas the current would bypass the resistor and would

therefore not be limited by the resistor, which would result in the destruction of the lamp.

Usually in a discharge device of this type the ballasting device is designed to absorb approximately 50 to 60% of the applied voltage. This voltage is the product of the current in amperes and the resistance in ohms of the series resistor and this product, divided by the effective length of the resistor in inches, must be less than the breakdown potential of the gas in volts per inch considering the non-emissive character of the resistor metal.

The foregoing description is related to utilization of a gas discharge lamp in an alternating current circuit. It will of course be understood that a lamp of the same general character may be utilized on a direct current circuit in which event only one of the resistor elements would be necessary since the current flow would be in one direction only.

While we have described a preferred embodiment, it will be understood that many modifications thereof are possible and we wish therefore not to be limited by the foregoing description but on the contrary solely by the claims granted us.

What we claim is:

1. A fluorescent lamp comprising an elongated tubular envelope, a gaseous atmosphere in said tubular envelope, a filamentary electron emitting cathode at each end of the device within the envelope, a resistor connected in series with each filamentary cathode, each resistor being positioned within the envelope adjacent its respective cathode, a pair of polarized terminal pins at each end of the envelope, the respective cathodes being directly connected to pins of one type and the resistors to pins of the other type, said lamp being adapted to insertion in a pair of polarized receptacles so that during an initial starting period the circuit extends through said cathodes and resistors in series and subsequently to the initial period the circuit extends through one of said resistors and its associated cathode, and thence through the arc discharge path to the end of the opposite resistor furthest removed from the associated cathode, said resistors having a potential drop per unit of length less than the breakdown potential of the gaseous atmosphere per unit of length, said resistors being alternately

in series with the discharge path and serving to limit the current through the lamp.

2. A fluorescent lamp comprising an elongated tubular envelope, a gaseous atmosphere in said tubular envelope, a filamentary electron emitting cathode at each end of the device within the envelope, a resistor connected in series with one of said cathodes, said resistor being positioned within the envelope adjacent its associated cathode, a pair of polarized terminal pins at each end of the envelope, the respective cathodes being directly connected at one end to pins of one type and the free ends of the resistor and of the cathode remote therefrom from being connected to pins of the other type, said lamp being adapted to insertion in a pair of polarized receptacles so that during an initial starting period the circuit extends through said cathodes and said resistor in series and subsequently to the initial period the circuit extends through said resistor and its associated cathode, and thence through the arc discharge path to the opposite cathode, said resistor having a potential drop per unit of length less than the breakdown potential of the gaseous atmosphere per unit of length, said resistor being in series with the discharge path and serving to limit the current through the lamp for direct current operation.
